CLAIM

The ornamental design for a coding matrix tool, as shown and described.

DESCRIPTION

FIG. 1 is a first front perspective view of the coding matrix tool, in unfolded configuration showing my new design; FIG. 2 is a rear perspective view thereof;

FIG. 3 is a front elevation view of the first panel thereof;

FIG. 4 is a front elevation view of the second panel thereof;

FIG. 5 is a front elevation view of the third panel thereof;

FIG. 6 is a front elevation view of the fourth panel thereof;

FIG. 7 is a front elevation view of the fifth panel thereof;

FIG. 8 is a rear elevation view of the fifth panel thereof;

FIG. 9 is a rear elevation view of the fourth panel thereof;

FIG. 10 is a rear elevation view of the third panel thereof; FIG. 11 is a rear elevation view of the second panel thereof; and,

FIG. 12 is a rear elevation view of the first panel thereof.

The broken line portions of the coding matrix tool are included for the purposes of illustrating environment only, and form no part of the claimed design.
